SENSITIVE RELAY

Frank G. Boucher, Tulsa, Okla., assignor to
 Standard Oil Development Company, a corpora-
 tion of Delaware

Application April 23, 1948, Serial No. 22,741

4 Claims. (Cl. 175—320)

1

This invention relates to an improved type of sensitive relay. In particular the invention relates to a novel relay construction permitting positive relay action in response to exceedingly small currents.

The increasing use of electronic control and analytical instruments in many industries has been accompanied by the need of improved electrical components of the circuits used. Thus at the present time, for example, presently known relays are not suitable in some applications. As is well known, a relay is an apparatus containing two electrical circuits with means responsive to a comparatively small change of voltage or current in one of the circuits to produce a comparatively large change of voltage or current in the other circuit. Relays generally employ an electromagnet energized by the less powerful circuit to open or close contacts of the circuit carrying the more powerful energy. When it is necessary to activate a relay with extremely small currents it is customary to employ a vacuum tube. While sensitive relays have been proposed, designed to work at relatively low currents, no relay presently available gives positive action for currents as low as 20 microamperes. It is, therefore, the principal purpose of this invention to provide an improved type of relay which will positively respond to the extremely small currents of the magnitude indicated, without the necessity of employing a vacuum tube for amplification.

Furthermore, in conventional relays, the relays are characterized by requiring a continuous flow of a substantial current through the less powerful circuit to maintain positive closure of the contacts of the more powerful circuit. It is, therefore, a further object of this invention to provide a relay which will maintain positive closure of the high power circuit while requiring no more than the minimum sensitizing current to flow in the low power circuit.

In accordance with the present invention, a sensitive relay is connected with a polarized relay and auxiliary electromagnetic elements in a novel manner. The electromagnetic elements referred to are so connected as to positively pull the sensitive relay arm against the relay contacts when the sensitive relay is activated, the closure of the sensitive relay operating the polarized relay to control circuits which may be used for the higher power circuits. Thus the sensitive relay in the apparatus of the invention, aided by auxiliary electromagnets, is only utilized to respond to an extremely low current, and is operative to control a polarized relay through which higher cur-

2

rents may be drawn. The apparatus of this invention will be better understood by reference to the accompanying drawing wherein is shown diagrammatically an embodiment of this invention.

Referring to the drawing, the numeral 1 generally indicates a sensitive relay comprising the elements 2, 4, 5 and 6. With the exception of the tip of the relay arm 4, this sensitive relay may be of conventional construction. For example, a suitable relay is the Weston 534 sensitive relay. It is to be understood, however, that any suitable sensitive relay may be employed. As diagrammatically shown, the relay comprises a field magnet 2, a coil 5 and a relay arm 4. In response to suitable currents in coil 5, the relay arm 4 is moved to right or left, dependent upon the current in coil 5. Sensitive relays of the type indicated generally are constructed in the nature of an ammeter, the relay arm corresponding to the needle of the ammeter.

In accordance with this invention the tip of the relay arm 4 is modified as diagrammatically illustrated. Positioned on the end of the relay arm 4 is a soft iron slug 6. Contacts 3 and 7 connecting to arm 4 are brought out from the arm so as to "sandwich" the iron slug. As will be seen, electromagnets will attract the iron slug causing contact 3 or 7 of arm 4 to positively close auxiliary circuits connected with polarized relay 8.

Again polarized relay 8 may be of conventional construction. This type of relay, as the name implies, is characterized by movement of the relay arm, when activated, to either of two positions and maintenance of the relay arm in the particular position until movement of the arm is again activated. Thus in the relay 8 illustrated, flow of current through coil 9 of the relay will cause relay arm 10 to move to the left against contact 11 and will maintain the relay arm against this contact.

Similarly, flow of current through coil 12 of the relay will cause the relay arm to move to the right against contact 13 and will also hold the relay arm against this contact. Thus relay arm 10 will always be either in the left or in the right position. Positioned on each side of the iron slug 6, are electromagnets 14 and 15. The armatures of the electromagnets are so positioned that they will be contacted on movement of the relay arm 4, to right or left. As will be developed, the function of these electromagnets is to attract the iron slug 6 to right or left, as the associated circuits are operated.

The armature of electromagnet 14 is connected to lead 16 which is connected to one

side of coil 9 of the polarized relay, generally identified by the number 8 on the drawing. As stated, this polarized relay may be of conventional construction. For example, a suitable type of polarized relay is the American Automatic Electric series P. H. D. polarized relay. The other side of coil 9 of the polarized relay is connected to the relay arm 10 and also to one side of the other coil 12 of the relay, which connection serves as a junction point for lead 17. Lead 17 is connected to a battery 18, and the other side of this battery is connected to conductors 19 and 21. Lead 19 is connected to the movable arm 4 of the sensitive relay. This connection is preferably made by spiraling a light lead as indicated by the number 20, so that movement of the arm 4 will not be impeded by the connection of the lead. Lead 21 is connected to a portion of the circuit to be hereinafter described. Similarly, the armature of electromagnet 15 is connected to conductor 22, which is connected to coil 12 of the polarized relay 8.

As described heretofore, on activation of the sensitive relay 1 by the flow of a control current through coil 5, the relay arm 4 will be moved either to the right or to the left. Movement of the arm to the right will close an electrical circuit running from the battery 18 through lead 19, arm 4, contact 7, the armature of electromagnet 15, lead 22, and coil 12 of the polarized relay. This will cause the arm 10 of the polarized relay to similarly move to the right against contact 13 and to close other contacts, which will be arranged in a load circuit. For the purposes of simplicity these loading contacts of the relay are not illustrated separately but are represented by contacts 11 and 13. Thus, when arm 10 engages contact 13 an external circuit through conductors 30 and 32 will be established and when arm 10 engages contact 11 an external circuit through conductors 30 and 31 will be set up. Similarly, when activating current is passed through coil 5 in the opposite direction, the arm 4 will be moved to the left to contact the armature of electromagnet 14, closing the electrical circuit from the battery 18, through coil 9 of the polarized relay.

As stated, the electromagnets 14 and 15 are operative to aid the movement of relay arm 4. This is accomplished by connecting one side of the electromagnet 14 to lead 23 which is connected to the contact 13 of the polarized relay. The other side of the coil of electromagnet 14 is connected to the junction point 24 of conductor 21 of the battery 18. Similarly one side of the coil of electromagnet 15 is connected to the contact 11 of the polarized relay, through conductor 25, while the other side of this coil is connected to junction point 24, connecting to lead 21 and the battery 18.

By nature of the circuits described, when the arm 4 of the sensitive relay is moved either to the right or to the left, the arm 10 of the polarized relay will similarly be moved to the right or to the left. For example, if arm 4 is moved to the right, a circuit will be established through the battery 18 and the coil 12 causing the arm 10 of the relay 8 to move to the right against contact 13. On connection of the arm 10 and the contact 13, a circuit will then be completed from the battery 18, lead 17, arm 10, contact 13, lead 23, electromagnet 14 and lead 21. This will cause a current to flow in the coil of electromagnet 14 setting up an electromagnetic force

attracting the iron slug 6 of the arm 4. The coil used, and the battery voltage supplied is so chosen, however, that insufficient pull will be exerted on the slug 6 to pull the arm 4 away from its position against the armature of electromagnet 15. However, sufficient pull is exerted by the electromagnet 14 so that if the arm 4 is caused to move somewhat to the left, the slug 6, will be pulled forcibly toward the electromagnet 14.

10 Contact of the relay arm 4, with the armature of electromagnet 14, will then close the circuits formerly described, through the coil 9 of the polarized relay and through the electromagnet 15, thereby activating the system for a response 15 in the opposite direction.

As described, therefore, the apparatus of this invention comprises a combination of a sensitive relay with a polarized relay. The circuits combining these relays are so arranged that on closure 20 of the sensitive relay, the polarized relay is caused to close load circuits and at the same time closes a circuit through an electromagnet adapted to pull the sensitive arm of the relay to the other of its two positions. By virtue of this arrangement 25 any current in the coil of the sensitive relay, sufficient to move the arm of the relay away from one of the contacts, will enable the electromagnets adjacent to the arm to positively close the circuits through the relay arm.

30 It will be apparent from the description of the apparatus given, that the apparatus comprises a means for securing a positive movement of the relay arm of a sensitive relay, making it possible to use exceedingly small currents to activate 35 the sensitive relay. As an example of the efficiency of this apparatus, a typical construction embodying the principles taught herein enabled positive action of the relay circuit with currents as low as 20 microamperes. The advantages 40 of the apparatus of this invention will therefore be apparent.

Having now fully described this invention, what is claimed is:

1. An improved relay apparatus comprising a sensitive relay having a relay arm adapted to be thrown to a first contact position upon being energized by a small current flowing through said relay in one direction and to a second contact position upon being energized by a small amount of current flowing through said relay in the opposite direction, electrical contacts in the said relay associated with each of said contact positions, a polarized relay provided with a first activation means adapted to throw said polarized relay to a first contact position and with a second activation means adapted to throw said polarized relay to a second contact position, means connecting said first activation means with the electrical contact associated with said first contact position of said sensitive relay, means connecting said second activation means with the electrical contact associated with said second contact position of said sensitive relay, a first electromagnetic means adapted to exert a small pull on the arm of said sensitive relay toward its first contact position, a second electromagnetic means adapted to exert a small pull on the arm of said sensitive relay toward its second contact position, means for energizing said first 65 electromagnetic means when said polarized relay is in its second contact position, and means for energizing said second electromagnetic means when said polarized relay is in its first contact position.

70 2. Improved relay apparatus according to claim

1 in which a mass of iron is provided on the movable arm of the sensitive relay adjacent said first and second electromagnetic means to aid the action of said first and second electromagnetic means.

3. An improved relay apparatus comprising in combination a sensitive relay of the ammeter type provided with a field magnet, a movable relay arm at least a portion of which is magnetic, at least two contact points, and a coil adjacent said relay arm adapted to move said arm in one of two directions so as to engage one of said two contact points, dependent upon the direction of current flow through said coil, electromagnets disposed adjacent each of said contact points, a polarized relay provided with a first coil adapted to throw said polarized relay to a first contact position and with a second coil adapted to throw said polarized relay to a second contact position, electrical contacts in said polarized relay associated with each of said contact positions, an electrical circuit connecting said first polarized relay coil with the first of said two sensitive relay contact points, an electrical circuit connecting said second polarized relay coil with

the second of said relay contact points, an electrical circuit connecting the contact points associated with the first contact position of said polarized relay with the electromagnet adjacent the second of said sensitive relay contact points and an electrical circuit connecting the contact points associated with the second contact position of said polarized relay with the electromagnet adjacent the first of said sensitive relay contact points.

4. Improved relay apparatus according to claim 3 in which the movable end of said sensitive relay arm engaging said contact points is provided with a small mass of soft iron.
